METHOD OF FORMING SLIDERS FOR SLIDE FASTENERS

Alfred E. Carlile, Meadville, Pa., assignor to Talon, Inc., a corporation of Pennsylvania
Filed June 9, 1958, Ser. No. 740,872
9 Claims. (Cl. 29—409)

This invention relates to sliders for slide fasteners, and more particularly to a method of forming sliders generally of the type disclosed in the patent to Sundback, No. 1,661,114, issued February 28, 1938, and Poux, No. 1,901,189 issued March 14, 1933.

It is the general practice to form sliders for slide fasteners from continuous length flat metallic stock by the so-called "coined" slider method as disclosed in the aforementioned patent or the so-called "flat formed" method. In both methods, the slider blanks are partially formed in the strip so as to provide a series of interconnected slider blanks. These slider blanks are then blanked therefrom so as to provide individual slider blanks. In forming the slider blanks by either method, a large amount of scrap results which, of course, is undesirable. Also, by either method partially formed slider blanks are individually transferred from one machine to another for performing the necessary sequence of operations thereon until the slider is completed. This individual handling of each slider blank and body for each forming operation is not only laborious and tedious but requires a number of pieces of expensive and complicated equipment and machines.

According to the present invention, there is provided an improved method of forming sliders wherein no scrap results from the fabrication of the slider bodies and the time for forming the same and the amount of equipment needed for such forming is reduced to a minimum. In the method of the present invention, a continuous length of metallic stock is progressively subjected to a series of forming operations by rolling so as to progressively produce a connected series of slider blanks that can be severed from the strip after the last rolling operation thereby eliminating the above mentioned disadvantages.

It is the general object of the present invention to provide a new and improved method of forming sliders which is simple and economical and, at the same time, efficient and effective.

It is another object of the invention to provide an improved method of forming sliders wherein a continuous length of round metallic stock is fed to and between a plurality of rolls which not only flatten the stock but simultaneously form a series of interconnected slider blanks in the strip.

It is a further object of this invention to provide a method of forming sliders from a continuous length metallic strip wherein the edges of the strip are formed to shape by means of contour rolls in a substantially continuous operation so as to provide a series of interconnected slider blanks with the outer contours completely finished by the contour rolling thereby eliminating any blanking operations which would result in producing scrap.

Various other objects and advantages of this invention will be more apparent in the course of the following specification, and will be particularly pointed out in the appended claims.

In the accompanying drawings, there is shown for the purpose of illustration, an embodiment and a modification thereof which my invention may assume in practice.

In these drawings:

FIG. 1 is diagrammatic plan view of the rolls for forming slider blanks of one type in accordance with my invention showing a continuous length of metallic strip passing therethrough to form slider blanks from the strip,

2

FIG. 2 is a diagrammatic side view of the rolls, as shown in FIG. 1, and, in addition, showing means for forming the diamond-shaped thickened portion on the strip by coining and means for severing the slider blanks from the strip.

FIG. 3 is a plan view of one of the slider blanks formed by this modified method after it has been cut from the formed strip and the flanges formed thereon,

FIG. 4 is a side view of the blank shown in FIG. 3,

FIG. 5 is a side view of a slider body after the wing portions of the slider blank have been bent to final form,

FIG. 6 is a plan view of the slider body shown in FIG. 5,

FIG. 7 is a diagrammatic plan view similar to FIG. 1, 15 of the rolls for forming the slider blanks of another type in accordance with the present invention, showing a continuous length of metallic strip passing therethrough to form the slider blanks from the strip,

FIG. 8 is a diagrammatic side view of the rolls as shown 20 in FIG. 7, and in addition showing means for severing the slider blanks from the strip,

FIG. 9 is a plan view of one of the slider blanks after it has been cut from the formed strip and the flanges formed thereon,

FIG. 10 is a side view of the slider blank shown in 25 FIG. 9,

FIG. 11 is a side view of a slider body after the wing 30 portions of the slider blank have been bent to final form, and

FIG. 12 is a plan view of the slider body shown in FIG. 11.

Referring more particularly to the drawings, there is shown in FIGS. 1 and 2, a pair of opposed flattening rolls 2 and a pair of opposed contour rolls 3 arranged in tandem relative to each other for shaping the strip to form 35 one type or coined slider blank in accordance with the present invention. These rolls 2 and 3 are secured to shafts 2a and 3a, respectively, which are adapted to be rotated by any suitable means (not shown). There is also provided with the contour rolls 3 preferably a pair 40 of opposed smooth surfaced rolls 5 which are arranged at right angles to the contour rolls 3. In FIG. 2 there is shown, in addition, a coining press 6 and a severing or cut-off die 7.

In practicing the invention, a round strip of metallic 45 stock is fed to and between the flattening rolls 2 whereby the strip is rolled and flattened to the desired thickness so as to provide a flat strip S. The flat strip then passes between the contour rolls 3 and the smooth surfaced rolls 5. These contour rolls 3 shape both edges of the strip as at 25, and the rolls 5 confine the flow of the metal of the strip during such shaping. In shaping the edges of the strip in such a manner, it will be seen that there is provided in the strip a series of connected shapes with each having the general configuration of a slider blank.

The strip S then passes to the coining die 6 where the blanks B are finally shaped in the strip and substantially a diamond-shaped thickened portion 8 is formed at spaced-apart intervals therealong so as to provide a series of interconnected slider blanks B with each blank consisting of a pair of wing portions 9 connected by a relatively narrow portion 10. The strip 3 then passes to the severing or cut-off die 7 wherein the slider blanks B are successively cut from the end of the strip. The individual blanks B are then fed to a suitable flanging die (not shown) wherein the marginal flanges 12 are bent up from the wing portions 9 thereof so as to provide an individual slider blank, as shown in FIGS. 3 and 4.

It will be seen then that this finished slider blank 70 consists of a pair of identical channeled wing portions 9 interconnected by relatively narrow portion 10 and the

raised diamond-shaped portion 8. The slider blank is then bent to completed form by bending the wing portions toward one another at the narrow portion 10, so as to provide a finished slider, as shown in FIGS. 5 and 6, having a pair of spaced-apart wing portions arranged in parallelism connected at one end by a neck portion whereby a channel is provided therebetween in a manner well known to those skilled in the art.

In FIGS. 7 through 12 of the drawings, there is shown equipment for forming another type of slider body which is more commonly known as the flat formed type. In FIGS. 7 and 8, there is shown a series of pairs of opposed contour rolls 12, 13 and 14 arranged in tandem which are secured to shafts 12a, 13a and 14a, respectively. These shafts are adapted to be rotated by any suitable means (not shown). With each of these pairs of contour rolls 12, 13 and 14, there is arranged on suitable shafts at right angles thereto, a pair of opposed flattening rolls 15, 16 and 17, respectively. In FIG. 8 there is shown in addition, severing or cut-off die 18.

In this method, round metallic stock is fed first to and between the first pair of contour rolls 12 and associated flattening rolls 15 whereby the stock is simultaneously flattened by the rolls 12 and both edges of the strip S are partially shaped, as at 30, by the contour rolls 12 so as to provide in the strip a series of connected shapes with each, as before, having the general configuration of a slider blank. The strip S then passes between the next pair of contour rolls 13 and associated flattening rolls 16 wherein the strip is further flattened and the edges of the strip shaped further so as to provide more pronounced slider blanks in the strip. The strip then passes between the final pair of contour rolls 14 and the associate flattening rolls 17 whereby the strip is rolled to its desired thickness and the edges of the strip are further shaped by the contour rolls 14 so as to provide a series of interconnected slider blanks B. The strip is then fed to the severing die 18 wherein individual slider blanks B are successively cut from the end of the strip. The blanks are then fed to a suitable flanging die (not shown), for forming marginal flanges 19 on the wing portions thereof.

As before, each of the blanks, as shown in FIGS. 9 and 10, consists of a pair of channeled wing portions 20 interconnected by a relatively narrow portion 21. The wing portions 20 are then bent toward one another at this narrow portion 21 so as to provide a completed slider body, as shown in FIGS. 11 and 12, having a pair of spaced-apart wing portions connected at one end by a neck portion.

It will be seen that the contour rolls partially form the edges of the strip so as to conform substantially to the outer contour of the slider blanks. All of the rolls together with the dies, are preferably timed so that each performs its operation on the strip and connected series of slider blanks at the same instant the others are performing operations on the strip and other blanks thereof. That is to say, the metallic strip S can be moved a certain distance and then stopped, at which times each piece of equipment performs an operation on the strip and a blank. Then the strip is moved until the next adjacent slider blank is in position to be operated on by the rolls or dies, and so on.

As a result of my invention, it will be seen that there is provided an improved method of forming sliders for slide fasteners which is more economical than previous methods, in that, sliders can be produced in a minimum amount of time and with a minimum amount of labor and equipment, and most important, my method is scrapless thereby resulting in a saving of metal which is a decided advantage and results in a reduction in cost of slider fabrication.

While I have shown and described an embodiment and modification thereof which my invention may assume in practice, it will be understood that these embodiments are

merely for the purpose of illustration and description, and that other forms may be devised within the scope of my invention as defined in the appended claims.

What I claim as my invention is:

- 5 1. The method of forming sliders of the class described by a series of successive operations, which includes the steps of progressively feeding a continuous strip of flat metallic stock between a pair of opposed contour rolls for deforming the marginal edges thereof so as to provide a connected series of partially formed slider blanks, feeding said strip to means for further deforming the same to the shape of a series of interconnected slider blanks which are substantially of a final deformed shape, and feeding said strip to severing means for cutting individual slider blanks from said strip.

10 2. The method of forming sliders of the class described by a series of successive operations, which includes the steps of progressively feeding a continuous strip of round metallic stock between a pair of rolls to flatten the stock, passing said strip between a pair of opposed contour rolls for deforming the marginal edges thereof so as to provide a connected series of partially formed slider blanks, feeding said strip to means for further deforming the same to the shape of a series of interconnected slider blanks which are substantially of a final deformed shape, and feeding said strip to severing means for cutting individual slider blanks from said strip.

15 3. The method of forming sliders of the class described by a series of successive operations, which includes the steps of progressively feeding a continuous strip of flat metallic stock between a pair of opposed contour rolls for deforming the marginal edges of the strip, feeding said strip to means for deforming the same to the shape of a series of interconnected slider blanks which are substantially of a final deformed shape, feeding said strip to means for forming a substantially diamond-shaped raised portion centrally on one side of each of said blanks, and feeding said strip to severing means for cutting individual slider blanks from said strip.

20 4. The method of forming sliders of the class described by a series of successive operations, which includes the steps of progressively feeding a continuous strip of round metallic stock between a pair of rolls to flatten the stock, passing said strip between a pair of opposed contour rolls for deforming the marginal edges of the strip so as to provide a connected series of partially formed slider blanks, feeding said strip to means for further deforming the same to the shape of a series of interconnected slider blanks which are substantially of a final deformed shape, feeding said strip to means for forming a substantially diamond-shaped raised portion centrally on one side of each of said blanks, and feeding said strip to severing means for cutting individual slider blanks from said strip.

25 5. The method of forming sliders of the class described by a series of successive operations, which includes the steps of progressively feeding a continuous strip of round metallic stock between a pair of flattening rolls and a pair of contour rolls, so as to simultaneously flatten the stock and deform the marginal edges of the strip so as to provide a connected series of partially formed slider blanks, feeding said strip to means for further deforming the same to the shape of a series of interconnected slider blanks which are substantially of a final deformed shape, and feeding said strip to severing means for cutting individual slider blanks from said strip.

30 6. The method of forming sliders of the class described by a series of successive operations, which includes the steps of progressively feeding a continuous strip of round metallic stock to a series of rolling units arranged in tandem, each of said units consisting of a pair of flattening rolls and a pair of contour rolls arranged at right angles thereto whereby the strip is simultaneously flattened and the marginal edges of the strip deformed as it passes between the flattening rolls and the contour rolls so as

to form the strip to the shape of a series of interconnected slider blanks which are substantially of a final deformed shape, and feeding said strip to severing means for cutting individual slider blanks from said strip.

7. In a method of forming sliders of the class described, the steps consisting of contour rolling the marginal edges of a strip so as to provide a series of connected slider blanks which are substantially of a final deformed shape, each of which has a pair of flat wing portions connected by a relatively narrow portion in strip form, severing the blanks apart, bending up marginal flanges on the wing portions, and finally bending the wing portions of each blank toward one another to substantially parallelism to provide a completed slider body.

8. In a method of forming sliders of the class described, the steps consisting of flattening a continuous strip of round stock by rolling, deforming the marginal edges of the strip by contour rolling so as to provide a series of connected slider blanks which are substantially of a final deformed shape, each of which has a pair of flat wing portions connected by a relatively narrow portion in strip form, severing the blanks apart, bending up marginal flanges on the wing portions, and finally bend-

ing the wing portions of each blank toward one another to substantially parallelism to provide a completed slider body.

9. In a method of forming sliders of the class described, the steps consisting of simultaneously flattening and roll deforming the marginal edges of a continuous strip of round metallic stock so as to provide a series of connected slider blanks which are substantially of a final deformed shape, each of which has a pair of flat wing portions connected by a relatively narrow portion in strip form, severing the blanks apart, bending up marginal flanges on the wing portions, and finally bending the wing portions of each blank toward one another to substantially parallelism to provide a completed slider body.
